UNITED STATES PATENT OFFICE.

HUGH COYLE, OF WASHINGTON, DISTRICT OF COLUMBIA.

FIRE-ESCAPE.

SPECIFICATION forming part of Letters Patent No. 510,343, dated December 5, 1893.

Application filed October 7, 1893. Serial No. 487,498. (No model.)

To all whom it may concern:

Be it known that I, HUGH COYLE, a citizen of the United States, residing at Washington city, in the District of Columbia, have invented certain new and useful Improvements in Fire-Escapes and Lowering Apparatus; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to fire-escapes, or other apparatus designed for safely lowering articles from one level to another, and it consists in the devices hereinafter described and claimed whereby the downward motion of the 20 person, or article, that is being lowered may be retarded at will, as well as in the construction of a rope or cable which constitutes the support for the said person or article.

Referring to the drawings Figure 1 is a view 25 showing the use of the improved rope in connection with a frictional device. Fig. 2 represents the improved frictional device. Figs. 3 and 4 are views of the rope or cable.

A represents a cable, rope, or some similar 30 flexible device, which as shown, may be secured to any suitable object, as a bedstead, or to any fixed support and which passes through a frictional device B that is adapted to slide upon it and to be grasped by the hands, or to 35 which may be attached a stirrup C or any other means for holding a body or object so that the body or object as it is being lowered may be suitably supported. The improved frictional device consists of a tube coiled between its ends so as to form two lateral loops 40 each of which may be grasped by a person. Such a tube can be used in lowering two persons at once, and has, therefore, greater utility than a tube which is bent into a single coil; 45 and moreover is better suited for the use of one person since that person can conveniently hold on to it with both hands. The ends of the tube are straight and in alignment and are slightly flared so as to present 50 a curved instead of an angular surface to the rope or cable. Abrasion of the rope is avoided

by this flaring feature. The tube is slightly larger than the rope so that the latter may be easily passed through it.

The rope or cable is made of strands of 55 strong steel, or other wire-thread a, covered with asbestos b, and between them is placed a filling c of plumbago, soap-stone, or any other lubricating material that will retain its position between the strands. The strands 60 and the filling are then covered with a woven envelope d of any material that is found to be available. Small portions of the lubricant pass through the meshes of the woven envelope when the latter is formed around 65 the rope, and also whenever the rope is handled, bent, or subjected to the pressure of the frictional device. The outside is, therefore, always lubricated and does not require the application of a lubricant, as do the surfaces of ropes as at present constructed. The 70 lubricant and the asbestos coverings of the wires make the rope fire-proof so that it will not be consumed when subjected to the action of fire. The rope thus not only embodies the 75 element of strength, but is non-combustible and possesses the quality of self-lubrication. It is also light and flexible and can be easily coiled for packing, or tied to an object like an ordinary rope. Fifty feet of this rope that 80 will sustain a weight of three hundred and twenty pounds weigh less than two pounds, and can be coiled so closely that it can be placed in an ordinary pocket.

When the apparatus is being used a person 85 may descend by grasping the frictional device, or he may partly support himself by placing his foot in a stirrup C or equivalent device, which may be attached to the said frictional device. After one person has descended another may pull up the rope and attach what was its lower end to some object, 90 letting the upper end fall to the ground, thus bringing the frictional device within his reach so that he also may descend. The stirrup or other supporting element will at such time automatically swing round into position for use. This operation may be repeated until all persons have descended. The speed 95 of descent can be reduced by throwing the part of the rope just below the frictional device to one side, as shown in Fig. 1, or by 100

turning the device itself so that the rope will bind against the curved surface at the ends of the tube.

I do not limit the use of my invention to 5 fire-escapes, for the apparatus may be employed to lower any heavy body whatever. By merely throwing the rope out of plumb by pulling the lower end to one side of a vertical line passing through the support for the 10 same, the frictional device will bind upon the rope and hold the heaviest articles in suspension.

The rope may be constructed of wires which are not covered with asbestos, but which have 15 between them a lubricant of the character described, and are covered with a suitable envelope. With this construction, if the lubricant be fire-proof, the rope will be non-combustible.

20 Having now fully described my invention, what I claim, and desire to secure by Letters Patent, is—

1. As an article of manufacture a frictional device for fire-escapes, or similar apparatus, 25 which consists of a tube bent so as to form

two complete separated and oppositely disposed loops, the ends of the tube being in alignment and flared and having their axes at right angles to the loops, substantially as described.

2. A rope or cable for fire-escapes, or similar purposes, formed of wires covered with asbestos, or other suitable refractory or non-combustible material, and having a lubricant, such as plumbago, or soap-stone, between 35 them, and surrounded by a woven envelope or casing, substantially as described.

3. A rope or cable for fire-escapes, or similar purposes, formed of wires which are surrounded by a woven or other suitable envelope or casing, the wires having between 40 them a suitable lubricant such as plumbago or soapstone, substantially as described.

In testimony whereof I affix my signature in presence of two witnesses:

HUGH COYLE.
